[57] CLAIM

The ornamental design for a display case, as shown and described.

DESCRIPTION

FIG. 1 is an isometric view of the display case showing our new design;

FIG. 2 is a top plan view thereof;

FIG. 3 is a front elevational view, the rear view being a mirror image thereof;

FIG. 4 is a right side elevational view of the display, the left side being a mirror image thereof;

FIG. 5 is a bottom plan view thereof;

FIG. 6 is a front elevational view of a second embodiment, the rear view being a mirror image thereof; and

FIG. 7 is a right side elevational view of FIG. 6, the left side being a mirror image thereof.

FIG. 1.**FIG. 2.**

FIG. 3.

FIG. 4.

FIG. 5.

FIG. 6.

FIG. 7.
